WELL DRILLING ROTARY

August R. Maier and John M. Shimer, Dallas,
Tex., assignors to Oil Well Supply Company, a
corporation of New Jersey

Application September 12, 1940, Serial No. 356,533

9 Claims. (Cl. 184—6)

This invention relates to improvements in well drilling rotaries and more particularly to improvements in a high speed rotary.

Our invention has in view to provide a forced lubrication system or means for such a rotary capable of adequately supplying lubricant to the moving parts of the rotary.

The invention further contemplates incorporating such a forced lubrication with a splash or bath lubricating system to insure proper lubrication under any and all conditions of operation.

We also provide our improved lubricating means constructed in and driven by the rotary structure whereby to provide a self-contained unitary device.

Further objects and advantages will become apparent from the following description taken in connection with the accompanying drawings, wherein:

Fig. 1 is a horizontal sectional view of a well drilling rotary embodying our invention, said section being taken on the broken line I—I of Fig. 2;

Fig. 2 is a vertical sectional view thereof taken on the line II—II of Fig. 1;

Fig. 3 is an enlarged detailed sectional view taken on the line III—III of Fig. 2;

Figs. 4 and 5 are detailed fragmentary sectional views taken on the lines IV—IV and V—V of Fig. 1, respectively; and

Fig. 6 is a schematic horizontal sectional view illustrating the lubrication of the rotary in the manner of our invention.

In the drawings, which illustrate a preferred embodiment of our invention, the rotary table 2 is rotatably supported on the base 3, as by means of a main bearing 4, said table having a central depending annular portion 5 and a terminal ring or flange 6 mounting a hold-down bearing or bushing 7, the latter engaging a coacting annular wall or portion 8 of the base 3.

The bearings 4 and 7 and the depending portion 5 of the table are enclosed within an upright housing 9 comprising an integral extension of the base proper 3, said housing and the periphery of the table having coacting annular portions providing a suitable labyrinth oil seal, generally designated 10, the construction of which is fully set forth in our companion application of even date, Serial Number 356,532, now Patent No. 2,254,183, dated August 26, 1941.

Extending laterally at one side of the table 2 and the housing 9, the base 3 is provided with a pinion shaft housing 12 for mounting a pinion shaft 13 having a pinion gear 14 thereon for

engaging and driving the table 2 by its ring gear 15. The housing 12 is separated from the table housing 9 by an intervening partition wall 16, which wall, together with the spaced end wall 17 of the housing 12, is horizontally bored to receive a bearing cage 18.

Said bearing cage 18 mounts and encloses pinion shaft thrust bearings 19 and roller bearing 20 in spaced relation, and the said bearings, pinion shaft 13, pinion 14 and cage 18 may be assembled and positioned in the bore of the housing 12 as a unit. 21 designates a sprocket secured to the outer terminal of the pinion shaft 13 for driving the rotary from a suitable power source, not shown.

For the purpose of mounting and enclosing portions of our lubrication system within the rotary structure, we provide the interior of the pinion shaft housing 12 of sufficient volume and proportions to permit the introduction and assembly of lubricating means therein. Likewise, the said housing is provided with a top access opening closed by a removable cover 22 and a side opening closed by a removable member 23.

The lower portion of the interior of the shaft housing 12 forms a lubricant sump or reservoir 24, and contains a lubricant pump 25, said pump being supported adjacent the pinion shaft 13 as by means of a bracket 26 carried by the closure member 23 at one side of the housing 12. The intake side of the pump is connected with the sump 24 through a submerged strainer 27 also preferably supported by the bracket 26. (See Fig. 3.)

The cage 18 for mounting shaft 13 is preferably of skeleton form, having openings 28 and ribs or portions 29 disposed between those end portions of the cage mounting and enclosing the bearings 19 and 20, and a pump gear 30 is extended through one of said openings 28 to mesh with a gear 31 secured to the pinion shaft 13 for driving the pump while the rotary is being driven from its source of power. The openings 28 around the cage 18 further aid in the assembly and inspection of the pump and its driving connection from the access opening closed by cover 22 on the top of the shaft housing 12.

The outlet or discharge side of the pump 25 is connected to a distributing conduit 32 having branch lines or conduits 33 and 34. A fluid pressure gage 35 may be connected in the line 32 as shown, and is preferably mounted upon the closure member 23 of the shaft housing 12 in such a manner as to provide a visual indication externally of the rotary, whereby the operator may

observe the pressure of the lubrication system. It will be seen that the pump, pressure gage, strainer, and their connections may be assembled as a unit with closure member 23 and its bracket 26, whereby the same may be readily applied to or removed from the rotary, either for assembly or repair purposes.

Branch oil line or conduit 33 extends over the bearing cage 18 and is further divided into lines 36 and 37 respectively supplying lubricant to the pinion shaft bearings and the table 2. The line or conduit 36 is connected with both pinion shaft bearings 19 and 20 in any suitable manner.

For example, we prefer to provide a fluid passage or conduit 33 formed in one of the ribs or portions 29 of the cage 18 and extending between said bearings, said passage being connected intermediate its length with the line 36 through a check valve 39, permitting flow of lubricant from line 36 to the bearings 19 and 20 through passage 36 and suitable ports or passages 40 leading to the respective bearings through the cage 18 and the bearing mounts. 61 designates a pressure relief valve for the system of conduits.

Line or conduit 37 passes through the partition wall 16 through provided openings therein and has an inclined portion 42 disposed above and over the pinion gear 14, said portion 42 being perforated for jetting lubricant toward the zone of meshing of said gear and the table gear 15. The terminal of conduit portion 42 is provided with an orifice which is disposed over the race of table bearing 4 for delivering lubricant thereto. Any suitable means may be provided for securing said terminal in proper relation to said bearing. The size of the perforations and orifice in the conduit portion is preferably small enough to insure a positive delivery of lubricant to the branch conduit 36 and hence to the pinion shaft bearings 19 and 20.

Branch line 34 likewise extends through the partition wall 16 and is disposed for delivery of lubricant to the hold-down bearing 7 of the table 2. Suitable conduits may be employed therefor, but we prefer to provide integral fluid passages 43 and 44 drilled in the housing portion 8 and terminating in an annular passage 45 about the bearing 7, said bearing having radial ports 46 in communication with said annular passage and with an annular passage or oil groove 47 in the inner face of the bearing to lubricate the rotation of the table extension 5 thereon.

In operation, the pump 25 supplies the system of conduits described to deliver a pressure supply of lubricant from the sump 24 to the pinion shaft bearings 19 and 20, the pinion and table gears 14 and 15, the hold-down bearing 7, and the main table bearing 4. The pressure feed of the lubricant is supplied in direct proportion to the speed and therefore to the lubrication requirements of the rotary by directly driving the pump from the pinion shaft in the manner stated.

The lubricant from the bearings 19 and 20 is returned directly by gravity to the sump 24 through overflow ports 48 in the cage 18 adjacent each of said bearings. Lubricant from pinion gear 14 is received in a well 49 therebelow between the partition wall 16 and the table housing portion 8, said well 49 being in communication with the supply reservoir 22 by ports 50 in the lower portion of the said partition wall.

Lubricant delivered to the main table bearing 75

from conduit portion 42 flows into an annular groove 51 inwardly of the bearing in the housing portion 8, from whence said lubricant passes outwardly through radial passages 52 (see Figs. 2 and 6) and into a settling reservoir or pocket 53 formed in the base 3.

The settling pocket 53 is substantially concentric with and below the table ring gear 15 and is of horseshoe shape, having its spaced ends extending toward the sump 24 and being separated therefrom by dams 54 at opposite sides of the rotary base, said dams being elevated with respect to the pocket 53 whereby the settling are retained in pocket 53 and the clear lubricant flows over the dams to the sump. 55 designates openings in the partition wall above the dams 54 to permit the said return flow of lubricant to the sump.

The lubricant from the hold-down bearing 7 likewise returns to the sump 24 by way of the settling pocket 53, said lubricant first being gathered in an annular well 56 surrounding the bottom of the table portion 5. Said well 56 is formed by the wall 8 of the rotary housing and an upstanding annular flange 57 formed on the member 6, which flange has an overturned terminal lip 58. The oil in the well 56 is subjected to the rotation of the table 2 and is moved up and over the lip 58 to fall by gravity into the settling pocket 53.

A supply of lubricant is introduced into the rotary base in any suitable manner, as by a filling opening 59 at one end of the base 3, the proper level of the lubricant being gaged as by a bayonet gage 60. The lubricant is thereby initially supplied throughout the rotary and its pockets and sumps or wells for employment thereof in the forced or pressure lubrication system described. Drain plugs 61 may be provided in the pocket 53 and well 49 for removal of the lubricant where desired.

Our invention further provides additional lubrication means in conjunction with the pressure system described, whereby the rotary and its parts may be lubricated under all conditions encountered in practice. Thus, the disposition and arrangement of the settling pocket 53, the well 49 and sump 24 provide a splash or bath system of lubrication operable in addition to the present system, or separately in the event that the pressure system becomes inoperative.

The depth of the lubricant may be such as to immerse the lower portion of the pinion gear 14 in the well 49, whereupon a continuous delivery of oil is had to the table gear 15 and therefrom to the main table bearing 4 and hold-down bearing 7 by gravity. The lubricant thus bathes the wearing surfaces of the table and falls into the settling pocket 53, ultimately returning to the sump 24 and well 49, the latter communicating with the sump by ports 59.

We prefer to substantially enclose the periphery of the pinion 14 to prevent excessive splashing of lubricant against the table and the seal 10, and therefore provide embracing side walls or splash guards 62 about said gear. Also, a wiper 63 may be provided for engaging the rear face of gear 14 to prevent further pressure accumulation by the lubricant carried by said gear, and pressure relief ports 64 may be provided through the partition wall 16 behind the upper portion of the gear, through which ports excess lubricant may escape to the sump 24.

Further lubrication of the pinion shaft bearings 19 and 20 may be provided by extending the pas-

sage 38 to the outermost end of the cage 18 and providing the same with a lubricant fitting or nipple 65 through which grease may be supplied to the said bearings as by a grease gun. The check valve 39 prevents a flow of grease into the tubes of the pressure system. Also, the overflow ports 48 may be of small area so as to prevent a free escape of the grease from the shaft bearings.

From the foregoing, it will be apparent that we have provided a complete and positive lubrication system which is capable of maintaining lubrication during operation of the rotary at the various speed requirements encountered in practice. For example, our lubrication system has been found to be entirely adequate for rotary speeds of from 500 to 1000 R. P. M. Further, in the event that the rotary is to be operated at slower speeds or in the event that the pressure lubricant means becomes inoperative, the rotary may be continued in operation and under such condition is satisfactorily lubricated by the splash and bath system, together with the provision for greasing the pinion shaft bearings.

Various modifications and changes are contemplated within the scope of the following claims.

We claim:

1. A well drilling rotary including a base, a table rotatably mounted thereon, means for driving the table including a shaft geared to the table, a housing enclosing the driving means and having a lubricant sump therein, a bearing for the shaft enclosed within the housing, a lubricant pump in said sump driven from said shaft, conduits supplying lubricant from the pump to the table mounting and to the table-driving means including a conduit to the bearing, said bearing conduit extending in the housing for connection with an external source of lubrication, and a check valve in said conduit between the pump and bearing preventing a flow of the externally applied lubricant to the pump.

2. A well drilling rotary including a base, a table rotatably mounted thereon, a gear on the table and a pinion therefor, said base including a housing enclosing the table mounting, gear and pinion, a pinion shaft, bearings supporting the shaft, a housing enclosing said pinion shaft and bearings, said shaft housing having a lubricant sump therein, the base having a lubricant well therein beneath the pinion having fluid communication with the sump, a lubricant pump mounted in the sump having driving connection with the pinion shaft, conduits supplying lubricant from the pump to the table mounting, table gear and pinion, and to the pinion shaft bearings, lubricant splash guards disposed on opposite sides of the periphery of the pinion, said base having a lubricant settling pocket below the table gear and mounting for receiving the gravity flow of lubricant therefrom, the base having a lubricant passage therein connecting the pocket and sump for return flow of lubricant to the latter, by-passing the lubricant well for the pinion, and an elevated dam in the base associated with the passage for controlling the said return flow of lubricant from the pocket to said sump.

3. A well drilling rotary including a base, a table rotatably mounted thereon, a gear on the table and a pinion therefor, said base including a housing enclosing the table mounting, gear and pinion, a pinion shaft, bearings supporting the shaft, a housing enclosing said pinion shaft and bearings, said shaft housing having a lubricant

5 sump therein, the base having a lubricant well therein beneath the pinion having fluid communication with the sump, a lubricant pump mounted in the sump having driving connection with the pinion shaft, conduits supplying lubricant from the pump to the table mounting, table gear and pinion, and to the pinion shaft bearings, lubricant splash guards disposed on opposite sides of the periphery of the pinion, said base having a lubricant settling pocket below the table gear and mounting for receiving the gravity flow of lubricant therefrom, said settling pocket being of horseshoe shape and having its spaced terminals disposed adjacent the sump, said splash guards extending and preventing lubricant flow between the pocket and well, the base having fluid passages therein communicating with the sump, and means in the base between the settling pocket terminals and the passages controlling the return flow of lubricant from the pocket to the sump.

4. A well drilling rotary including a base, a table rotatably mounted thereon, said base including a housing enclosing the table mounting, means for driving the table including a shaft and pinion geared to the table, a second housing enclosing the driving means and having a lubricant sump therein, a lubricant pump in the sump driven from the shaft, conduits supplying lubricant from the pump to the table mounting and pinion, said base having a lubricant well at least partially enclosing the pinion receiving the lubricant supplied thereto by the pump and in lubricant communication with the sump, and said base having a settling pocket disposed to receive a return flow of lubricant from the table and its mounting, said pocket having communication with the sump and by-passing the well for separate return flow from the pocket to the sump.

5. A well drilling rotary including a base, a table rotatably mounted thereon, said base including a housing enclosing the table mounting, said base also having a lubricant settling pocket therein below the table disposed to receive a gravity flow of lubricant therefrom, a pinion for driving the table, a second housing having a lubricant sump therein, one of said housings having a lubricant well supplying lubricant to the pinion, said well being in communication with the sump for a flow of lubricant from the latter to said well, said sump being separated from the table housing by a partition wall, means preventing a flow of lubricant from the pocket to the well, said partition wall having an opening laterally beyond the well connecting the sump and pocket for lubricant flow from the pocket to the sump, by-passing said well, means adjacent said passage for controlling the said flow from the pocket, and means supplying a pressure flow of lubricant from the sump to the table mounting and pinion.

6. A well drilling rotary including a base, a table rotatably mounted thereon, said base including a housing enclosing the table mounting, said base also having a lubricant settling pocket therein disposed to receive a gravity flow of lubricant from the table and its mounting, a second housing having a lubricant sump therein, a pinion geared to the table intermediate the sump and pocket, means supplying lubricant under pressure from the sump to the table mounting and pinion, said base having a lubricant well beneath the pinion out of lubricant communication with the pocket and receiving the lubricant supplied to the pinion, said well being in communication

with the sump for return of said lubricant to the latter, and means in the base permitting and controlling a return flow of lubricant from the pocket laterally beyond and out of lubricant communication with the well.

7. A well drilling rotary including a base, a table rotatably mounted thereon, said base including a housing enclosing the table mounting, said base also having a lubricant settling pocket therein disposed to receive a gravity flow of lubricant from the table and its mounting, a second housing having a lubricant sump therein, a pinion geared to the table intermediate the sump and pocket, means supplying lubricant under pressure from the sump to the table mounting and pinion, said base having a lubricant well beneath the pinion out of lubricant communication with the pocket and receiving the lubricant supplied to the pinion, said well being in communication with the sump for return of said lubricant to the latter, said pocket being in the form of a horseshoe having the ends thereof terminating laterally on opposite sides of and out of lubricant communication with the well, and a partition wall between the housings having lubricant passages adjacent the ends of the pocket in lubricant communication with the pocket and sump for return flow of lubricant to the latter from the sump.

8. A well drilling rotary including a base, a table rotatably mounted thereon, said base including a housing enclosing the table mounting, said base also having a lubricant settling pocket therein disposed to receive a gravity flow of lubricant from the table and its mounting, a second housing having a lubricant sump therein, a pinion geared to the table intermediate the sump and pocket, means supplying lubricant under pressure from the sump to the table mounting and pinion, said base having a lubricant well beneath the pinion out of lubricant communication with the pocket and receiving the lubricant supplied to

the pinion, said well being in communication with the sump for return of said lubricant to the latter, said pocket being in the form of a horseshoe having the ends thereof terminating laterally on opposite sides of and out of lubricant communication with the well, and a partition wall between the housings having lubricant passages adjacent the ends of the pocket in lubricant communication with the pocket and sump for return flow of lubricant to the latter from the sump, said base having means between the ends of the pocket and sump controlling said return flow of lubricant from the pocket.

9. A well drilling rotary including a base, a table rotatably mounted thereon, said base including a housing enclosing the table mounting, said base also having a lubricant settling pocket therein disposed to receive a gravity flow of lubricant from the table and its mounting, a second housing having a lubricant sump and access openings therein, a pinion geared to the table intermediate the sump and pocket, cover plates for said openings to maintain a lubricant-tight housing, independently removable pressure lubricating means mounted on one of said cover plates and enclosed within the housing and having fluid connections with the sump, means for driving the pinion, said lubricating means being driven by said pinion driving means, conduits supplying lubricant from said lubricating means to the table mounting and to the pinion driving means, said base having a lubricant well beneath the pinion out of lubricant communication with the pocket and receiving the lubricant supplied to the pinion, said well being in communication with the sump for return of said lubricant to the latter, and means in the base permitting and controlling a return flow of lubricant from the pocket laterally beyond and out of lubricant communication with the well.

AUGUST R. MAIER.
JOHN M. SHIMER.
